[57] CLAIM

The design for an aquarium gravel cleaner, as shown and described.

DESCRIPTION

FIG. 1 is a perspective view of an aquarium gravel cleaner showing my new design;

FIG. 2 is a bottom plan view thereof;

FIG. 3 is a top plan view thereof;

FIG. 4 is a front elevational view thereof;

FIG. 5 is a right side elevational view thereof, the left side being a mirror image of the right side shown; and

FIG. 6 is a rear elevational view thereof.

The broken line representation of an aquarium and a hose in FIG. 1 is for purposes of illustration only.

FIG.-1

FIG.-2

FIG.-3

FIG.-4

FIG.-5
